UNITED STATES PATENT OFFICE.

EWALD LANGERFELD, OF NEW YORK, N. Y.

GUARD CHAIN AND HOOK.

SPECIFICATION forming part of Letters Patent No. 296,022, dated April 1, 1884.

Application filed January 14, 1884. (No model.)

To all whom it may concern:

Be it known that I, EWALD LANGERFELD, residing at No. 26 East Twenty-third street, in the city of New York, in the county of New York and State of New York, have invented a new and useful Guard Chain and Hook, of which the following is a specification.

My invention relates to improvements in guard chains and hooks, by which keys and other articles are attached to garments; and the object of my improvement is to provide a hook and chain that may be securely and conveniently attached to the edge of a garment or pocket. I attain these objects by the hook and chain illustrated in the accompanying drawing, which is a perspective view thereof.

The tongue A and back B are made together, so as to form a hook to fit over the edge of a garment. This hook A B is made as nearly rigid as possible. On each side of the tongue A is a spring, I and I, attached to the back B at their upper ends, and connected by the rigid part C at their lower ends, so as to form a flexible jaw outside of and independent of the tongue A. The springs I and I are shaped to close the jaw I C I inward toward the back B. At the lower end of the jaw I C I are teeth D and D. This jaw I C I and back B are made together, so as to form a grip. The guard-chain E G is attached to the middle of the tongue A instead of the lower end, as chains are in ordinary guard chains and hooks. This is done for the purpose of reducing the strain tending to open the hook A B when the chain

E G is pulled at, the leverage being thus reduced one-half. Another advantage of attaching the chain to the middle of the tongue is that it prevents the hook from leaning forward or backward, as it would if the chain were fastened at either end of the tongue, and were pulled at.

To attach the hook the end of the back B is placed behind the edge of the garment, the jaw I C I is then raised outwardly, so that the points of the teeth D D will clear the edge of the garment. The whole is then pushed down and the jaw I C I let go, then the teeth D D will fasten themselves into the cloth and hold the hook where placed. The jaw I C I being separate from the tongue A, a pull on the chain E G will not pull out the teeth D D. The outlines of the hook may be made in various forms, or the hook may be all or partly made of wire, or the springs may be made of coiled wire and placed on the top or at any other part.

What I claim as my invention, and desire to secure by Letters Patent, is—

1. The combination of the rigid hook and tongue A B and flexible grip I C I with teeth D D, substantially as described.
2. The rigid hook and tongue A B, with guard-chain E G, attached to the middle of the tongue A, for the purpose specified.

EWALD LANGERFELD.
